FIREARM

Carl G. Swebilius, New Haven, Conn.

Application October 22, 1931. Serial No. 570,375

13 Claims. (Cl. 42—16)

This invention relates to firearms and has for an object an efficient and serviceable single-shot rifle which is capable of being taken down easily and quickly.

5 Other objects, novel features and advantages of this invention will be apparent from the following specification and accompanying drawings, wherein:

Fig. 1 is a fragmentary side elevation of a rifle 10 embodying the invention;

Fig. 2 is a similar view of the rifle taken down;

Fig. 3 is a section on the line 3—3 of Fig. 1;

Fig. 4 is a fragmentary side elevation of the receiver partly in section, the rifle being cocked;

15 Fig. 5 is a similar view with the breech bolt unbreched;

Fig. 6 is a section on the line 6—6 of Fig. 4;

Fig. 7 is a section on the line 7—7 of Fig. 5;

20 Fig. 8 is a fragmentary bottom view of the receiver, and

Fig. 9 is a fragmentary section through the receiver.

The rifle is provided with a standard stock 10 which supports a housing 11 open at its front 25 and upper ends and in which are mounted the hammer and trigger 13 and 13a. The receiver 12 closes this housing and is detachably connected thereto as will later be described. The housing 11 carries an upwardly extending pro-

30 jection 14 having an aperture 15 through which the rear end of the breech bolt reciprocates, the front end of the aperture being counter-sunk at 15a to receive a projection 16 extending from the rear end of the receiver 12. At the front

35 end of the receiver 12 there is provided a downwardly extending projection 17 which closes the front end of the housing 11. The projection 17 is recessed at 18 to receive shoulders 19 formed on the inner walls of the housing 11 and is also

40 provided with a tongue 20 which fits into the groove formed between the inner ends of the shoulders 19. In this tongue there is provided an oblique slot 21 through which extends a pin 22. At one end this slot is countersunk to re-

45 ceive the shoulder 23 of the pin 22 which is slidably supported by the housing 11 and passes through the shoulders 19. The smaller end of the pin 22 is provided with a button 24 against which bears the end of a spring 25 which normally maintains the button 24 beyond the surface of the housing 11. The pin 22 serves to lock together the housing and the receiver.

50 In taking down the gun, the button 24 is pushed inwardly, thus moving the shoulder 23 out of the countersunk end of the slot 21 whereupon

the front end of the receiver may be moved upwardly about its rear end as a center sufficient to disengage the slot 21 from the pin 22 and the shoulders 19 from the recesses 18 after which the barrel and receiver may be moved forward 60 to withdraw the shoulder 16 from the recess in the projection 14. The reverse procedure is followed in assembling the rifle.

The breech end of the barrel extends into the receiver beyond the cartridge slot 12a and is seated in a recess formed therein, the barrel being provided with threads which engage corresponding threads in the receiver to secure the barrel to the receiver. That portion of the barrel extending into the receiver is provided with 70 a long taper for guiding a cartridge into the cartridge chamber in the end of the barrel and is slotted in register with the slot 12a. The breech bolt 30 is provided at its forward end with extractors 31 of the usual type and is provided with a firing pin 32 slidably arranged in a groove extending longitudinally of the breech bolt. The rear end of the breech bolt is enlarged to provide a shoulder 33 which engages the rear end of the receiver to limit inward movement of the breech bolt and thus prevent the front end of the breech bolt from moving too far into the breech when there is no cartridge 80 in the chamber.

A locking block 34 is pivotally supported by the 85 breech bolt and has an arm 34a which extends downwardly through a groove in the bottom of the receiver 12 and into a recess in the end of the action rod 35. The receiver is provided with a pair of recesses forming shoulders 36 with which 90 projections 37 on the locking bolt 33 are adapted to contact for locking the gun in breeched condition. In the locking block, there is provided a slot across which extends a pin 38 that is adapted to be engaged by a lug 39 on the firing pin for 95 the purpose of maintaining the locking bolt in locking position. A spring 40 tends to hold the firing pin in proper position to engage the lug 39 with the pin 38. On the front end of the action rod 35 there is provided a grip member 41, by 100 means of which the action rod may be operated.

Fig. 4 shows the gun in breeched condition, the projections 37 of the locking bolt being engaged with the shoulders 36 of the receiver and the lug 39 of the firing pin being engaged with the pin 38. Upon release of the hammer 13, the firing pin is driven forward, thus exploding the cartridge and firing the gun. The forward movement of the firing pin disengages the lug 39 from the pin 38, whereupon a rearward pull on the grip 41 will 110

slide the action rod rearwardly, thereby turning the locking block to disengage the projections 37 from the shoulders 36 and causing rearward movement of the breech bolt to the position shown in Fig. 5. The rearward movement of the breech bolt cocks the hammer in the usual manner and uncovers the cartridge opening 12a in the receiver, thereby permitting the insertion of a cartridge into the cartridge chamber, the exploded cartridge having been ejected by means of the ejector later to be described. Forward movement of the action rod will draw the breech bolt into breeching position and again lock it in such position.

15 The ejector comprises a tooth 42 on the end of a metal strip 43, arranged in a slot 43' in the wall of the receiver. The tooth 42 projects through an aperture in the wall of the receiver into the path of the breech bolt and is adapted to ride in a groove 44 provided in the breech bolt. A spring 45 bears against the strip 43 and forces the tooth 42 inwardly into the bore of the receiver, this spring being held by a screw 46. As the breech bolt moves forward, the extractor is 25 engaged and moved outwardly against the action of the spring 45. On the rearward stroke of the breech bolt, the tooth 50 engages the end of the exploded cartridge carried by the extractors 31 and projects the same through the cartridge slot 30 in the well-known manner.

I claim:

35 1. A take-down firearm comprising a stock portion and a barrel portion, a recess in the stock portion, a projection on the barrel portion adapted to be received in said recess, interlocking means on said stock and barrel portions to prevent longitudinal relative movement thereof, a spring-pressed pin extending transversely of the stock portion and having one end projecting beyond the surface thereof, a slot in the barrel portion adapted to receive said pin, inter-engaging means on said pin and barrel portion for locking the barrel and stock portions against relative angular movement.

40 2. A take-down firearm comprising a stock portion and a barrel portion, a recess in the stock portion, a projection on the barrel portion adapted to be received in said recess, a spring-pressed pin extending transversely of the stock portion 50 and having one end projecting beyond the surface thereof, and inter-engaging means on said pin and barrel portions for locking the barrel and stock portions against relative angular movement.

45 3. In a firearm, a receiver, a breech bolt slidably mounted therein, a locking block pivoted to said breech bolt, inter-engageable means on said locking block and receiver for locking the breech bolt in firing position, a firing pin slidable on said breech bolt, means on said firing pin engageable in one position thereof with the locking block to hold the same in locking position, an arm extending from said locking block, and an action slide having a recess into which said arm projects.

50 4. In a firearm, a cylindrical receiver having a lateral cartridge slot, a barrel threaded into the front end of the receiver and projecting beyond the forward end of said slot, the rear end of said barrel being interiorly tapered and cut away in register with said slot.

55 5. In a firearm, a cylindrical receiver, a breech bolt slidably mounted in said receiver, a locking block pivoted to said breech bolt, an arm extending from said locking block, said receiver having

a longitudinal slot through which said arm extends and a transverse slot forming shoulders engageable by said locking block when the breech bolt is in firing position, and an action slide having a recess into which said arm projects.

60 6. In a firearm, a cylindrical receiver, a breech bolt slidably mounted in said receiver, a locking block pivoted to said breech bolt, an arm extending from said locking block, said receiver having a longitudinal slot through which said arm extends and a transverse slot forming shoulders engageable by said locking block when the breech bolt is in firing position, an action slide having a recess into which said arm projects, a firing pin slidable on said breech bolt, and means on said firing pin engageable in one position thereof with the locking block to hold the latter in locking position.

65 7. In a take-down firearm, a stock portion comprising a housing, a barrel portion comprising a cylindrical receiver closing said housing, releasable means for locking said stock and barrel portions in operative relation, a breech bolt slidably mounted in said receiver and having a portion projecting beyond the rear end of the receiver, a shoulder on the projecting portion adapted to engage the receiver to limit inward movement of the breech bolt, an action slide extending into said housing, and connections between said slide and breech bolt for actuating the latter by the former.

70 8. In a take-down firearm, a stock portion comprising a housing, a barrel portion comprising a cylindrical receiver closing said housing, releasable means for locking said stock and barrel portions in operative relation, a breech bolt slidably mounted in said receiver and projecting beyond the rear end thereof, said projecting portion being of greater diameter than the remainder to provide a shoulder adapted to engage the receiver to limit inward movement of the breech bolt, an action slide extending into said receiver, and connections between said slide and breech bolt for actuating the latter by the former.

75 9. In a take-down firearm, a stock portion comprising a housing, a barrel portion comprising a cylindrical receiver closing said housing, releasable means for locking said stock and barrel portions in operative relation, a breech bolt slidably mounted in said receiver, a locking block pivoted to said breech bolt, inter-engageable means on said locking block and receiver for locking the breech bolt in firing position, an arm extending from said locking block, and an action slide extending into said housing, said action slide having a recess into which said arm projects.

80 10. In a take-down firearm, a stock portion comprising a housing, a barrel portion comprising a cylindrical receiver closing said housing, releasable means for locking said stock and barrel portions in operative relation, a breech bolt slidably mounted in said receiver, a locking block pivoted to said breech bolt, inter-engageable means on said locking block and receiver for locking the breech bolt in firing position, an arm extending from said locking bolt, said receiver having a longitudinal slot through which said arm extends, and a transverse slot forming shoulders engageable by said locking block when the breech bolt is in firing position, and an action slide extending into said housing, said slide having a recess into which said arm projects.

85 11. In a take-down firearm, a stock portion comprising a housing, a barrel portion comprising

- ing a cylindrical receiver closing said housing, releasable means for locking said stock and barrel portion in operative relation, a breech bolt slideably mounted in said receiver, a locking block pivoted to said breech bolt, inter-engageable means on said locking block and receiver for locking the breech bolt in firing position, an arm extending from said locking bolt, said receiver having a longitudinal slot through which said arm extends, 5 a transverse slot forming shoulders engageable by said locking block when the breech bolt is in firing position, an action slide extending into said housing, said slide having a recess into which said arm projects, a firing pin slidable on said breech bolt, and means on said firing pin engageable in one position thereof with the locking block to hold the latter in locking position. 10
12. In a take-down firearm, a stock portion comprising a housing, a barrel portion comprising a cylindrical receiver closing said housing, a recess in said stock portion, a projection on said receiver adapted to be received in said recess, inter-locking means on said stock and barrel portions to prevent relative longitudinal movement of said portions, said means being engageable by relative 15 angular movement of said stock and barrel portions with said projection seated in said recess, a spring-pressed pin extending transversely of the stock portion, a slot in the barrel portion adapted to receive said pin, and inter-engaging means on said pin and barrel portion for locking the barrel and stock portions against relative angular movement. 20
13. A take-down firearm comprising a stock portion and a barrel portion, a recess in said stock portion, a projection on the barrel portion adapted to be received in said recess, inter-locking means on said stock and barrel portions to prevent relative longitudinal movement of said portions, said means being engageable by relative 25 angular movement of said stock and barrel portions with said projection seated in said recess, a spring-pressed pin extending transversely of the stock portion, a slot in the barrel portion adapted to receive said pin, a tapered shoulder on said pin, a recess in said barrel portion to receive said shoulder for locking the barrel and stock portions against relative angular movement. 30
